(Cl. D52—1)

FIG. 1.

FIG. 2

Figure 1 of the drawing is a view in front elevation of a front panel of time-controlled apparatus showing our new design.

Figure 2 is a view in side elevation of the front panel shown in Figure 1 mounted on a housing which is shown in phantom lines.

The dominant features of the design reside in the front panel shown in full lines.

We claim:

The ornamental design for a front panel of time-controlled apparatus, as shown and described.
